UNITED STATES PATENT OFFICE

EDWARD H. STEERE AND CLARENCE C. STEED, OF ASHEBORO, NORTH CAROLINA, ASSIGNEES OF ONE-FOURTH TO N. M. CRANFORD AND ONE-FOURTH TO C. C. CRANFORD, BOTH OF ASHEBORO, NORTH CAROLINA, AND ONE-FOURTH TO SAID STEERE AND ONE-FOURTH TO SAID STEED

HOSIERY DRIER

Application filed July 7, 1930. Serial No. 466,309.

The present invention relates to improvements in means for drying and shaping knitted garments, and is particularly adapted for drying hosiery.

5 In the manufacture of textile garments, and particularly hosiery, it is customary to dry the same over forms, and in order to prevent undesirable shrinking of the garment and maintain it in an unwrinkled condition during the operation, clamping means are provided for retaining the garment in position over a suitable form.

10 While the present improvements are adapted for use in drying garments of various kinds, they are, as before noted, particularly adapted for drying hosiery, and such an embodiment thereof is illustrated in the accompanying drawings.

15 In the drawings:

20 Figure 1 is an elevation of a drying apparatus, including a plurality of hosiery forms, having an embodiment of the present invention applied thereto.

25 Figure 2 is a horizontal section, on an enlarged scale, on the line 2—2 of Figure 1.

Figure 3 is an elevation, on an enlarged scale, of part of the means shown in Figure 1.

30 Figure 4 is a transverse section, on substantially the same scale as Figure 3, on the line 4—4 of Figure 1.

Figure 5 is a transverse section substantially on the line 5—5 of Figure 2.

35 Referring to the drawings, in the several figures of which like parts are designated by the same reference characters, the embodiment of the invention illustrated includes a plurality of hosiery forms, each comprising a base or pedestal section 1, and a body 2, of substantially elliptical form in cross section, which is connected with the pedestal or base by a neck 3.

40 As is customary, the body 1 having the form of the garment to be dried is of tubular construction, and the several forms are shown as being mounted on and in communication with a common conduit 4 for the steam, heated air, or other drying medium employed.

45 A clamping means including two bell crank levers is associated with each of the forms. The bell cranks of each pair of

clamps each include an upright arm 5 and a laterally extending arm 6 and, as shown, said bell cranks are pivotally mounted as at 7 on a rail or frame member 8 which is supported by brackets 9 connected with and extending forward from certain of the base sections 1 of the forms. The rail or frame member 8 extends throughout the series of forms and is provided at its ends and at suitable intermediate points with forwardly projecting ears 10 in which is mounted a rock shaft 11 that will be hereinafter more particularly referred to.

55 As shown, the brackets 9 are secured by bolts or screws 15 to the form base 1 and the rail 8 is connected by a suitable fastening means 16 to said brackets. It is not necessary to connect the rail 8 with each of the forms, but it merely serves to tie the several forms together and provide a firm support for the several clamping means.

60 The bolts or screws 15 which secure the rail carrying brackets in position, may also be the means for connecting form bases 1 to the conduit 4.

65 Laterally projecting arms 6 of each pair of bell cranks are so constructed that the free ends thereof are in overlapping relation as shown particularly in Figure 3, and one of said arms is provided adjacent its free end with a forwardly projecting member 17. To the free end of the arm 5 of each bell crank is adjustably connected a jaw member 20 which is adapted to cooperate with the adjacent edge of the form 2 to clamp a stocking closely upon said form and hold it against shrinking while being dried.

70 Preferably, as shown, each jaw member is shaped to conform to the edge of the form and it is provided with a lining of felt or other suitable absorbent material. An important feature of the improvements is that the jaws and form are so related that a minimum amount of contact with the garment being dried is provided and there is no danger of 75 the garment being marred as frequently occurs when the clamping means is related to the form so that it contacts with or bears against opposite faces thereof as distinguished from cooperating with the side edges.

The jaws 20, are, as above noted, adjustable with relation to the bell cranks by which they are carried. As shown, the jaw has a slot 20a formed therein and screws 21 extend through such slot and into the head at the outer end of the member 5 of the bell crank.

The members 5 of the two bell cranks associated with each form are connected by a spring 30, and this is so related to the pivots 7 of the bell cranks that the tension of the spring acts to maintain the two members of the clamp in operative relation with the form, or in the open inoperative position to which said clamping members are moved when the dried garments are to be removed from the forms.

As shown in Figure 3, the spring 30 is moved from a position above the horizontal plane of the pivots 7 to a position below such plane when the bell cranks are rocked to move the jaws from operative relation to inoperative relation. Such outward movement of the clamping device is shown as being limited by suitable stops 60 provided on the rail or frame 8.

The rock shaft 11 is provided at one end with a suitable handle 11a and at suitable points in its length with fingers 40. The fingers 40 are spaced along the rock shaft so that each of them will be in alignment with the projection 17 on one of the members of each clamp. Therefore, by rocking the shaft, a pressure may be exerted on the projection 17 and thereby the bell cranks will be positively rocked from the operative position shown at the left in Figure 3 into the open position shown at the right in the same Figure, thus releasing the clamping means of each of the forms. A spring 50 is preferably provided for holding the rock shaft in position where the fingers 40 thereof will permit the members of the clamp to be closed at will, upon the forms, and after the handle 11a has been released, and the shaft returned to its normal position, the several members may be readily and independently closed or moved into the operative position with relation to the form.

It is believed that the operation and advantages of the improvements will be readily understood from the foregoing description in connection with the drawings.

It is customary in hosiery mills for a single attendant to operate a series of forms, and it will be understood that a single rock shaft 11 is to be employed with each group.

As shown in Figure 1, stockings have been applied to each of the three forms at the left hand side of the group, but as yet stockings have not been slipped over the forms at the right. As the operator places a stocking in position upon either of the right hand forms (Figure 1), a very slight pressure upon the open jaws will bring them into closed relation with the form and in position to clamp

the stocking between the jaws and the edges of the form 2.

While the garments applied to one set of forms are drying, the attendant can be removing dried garments from another set.

When the garments on any group of forms are sufficiently dried, the attendant by merely rocking the shaft 11 can move all of the clamping devices into inoperative relation to the form (as shown at the right in Figures 1 and 3) and then readily strip the dried garments from the several forms.

It will be understood that in the drawings some of the parts are illustrated more or less diagrammatically and except where specifically noted in the appended claims it is not desired to limit the invention to the exact arrangement shown, as there can, of course be considerable variation in details without departing from the invention.

We claim:

1. Means for drying and shaping garments comprising a drying form, two pivotally mounted clamping members adapted to co-operate with said form and having opposite directed lateral arms which are in overlapping relation when the clamps are in operative relation to the form, a spring connecting the clamps and acting to hold them in either operative or inoperative relation to the form, and a manually oscillatable member adapted to engage one of said overlapping clamp arms and move the clamps away from the form.

2. Means for drying and shaping garments comprising a drying form, a pair of bell cranks mounted to rock about parallel axes and each having one arm provided with a jaw-like member adapted to engage an edge of the form, the other members of said bell cranks having their free ends in overlapping relation when said jaws are in operative relation to the form, a spring connecting the jaw carrying members of the bell cranks and adapted to hold the jaws in operative relation to the form or out of contact therewith, and means for positively rocking one of said bell cranks about its pivot to move the jaws away from the form.

3. Means for drying and shaping garments comprising a drying form, a pair of bell cranks, a jaw adjustably secured to one arm of each bell crank and adapted to engage one edge of the form, the other arms of said bell cranks being in engaging relation when the parts are positioned so that the jaws are in operative relation to the form, a spring connecting the jaw carrying arms of the bell cranks and adapted to hold them in position to hold the jaws either in contact with the form or away therefrom, and means for positively moving the bell cranks to carry the jaws from operative relation to the form.

4. In a garment drying and shaping means, the combination of a plurality of drying

forms, means for clamping a garment on each form comprising a pair of opposed bell crank levers, one arm of each said bell crank being adapted to cooperate with the form to hold 5 a garment in position thereon and the free ends of the other arms of said levers being in overlapping relation, a spring connecting the members of each pair of levers and adapted to hold them in either operative or inoperative 10 position with relation to the associated form, and a rock shaft extending past all of the forms and provided opposite each end thereof with a projection adapted to cooperate with the overlapping sections of the 15 arms of the adjacent pair of bell crank levers to positively rock said levers into inoperative relation to the forms as said shaft is actuated.

5. In a garment drying and shaping means, the combination of a plurality of drying 20 forms, a bar extending past all of the forms, means for clamping a garment on each form comprising a pair of opposed bell crank levers fulcrumed on said bar, one arm of each said bell crank being adapted to cooperate with 25 the form to hold a garment in position thereon and the free ends of the other arms of said levers being in overlapping relation, a spring connecting the members of each pair of levers and adapted to hold them in either operative 30 or inoperative position with relation to the associated form, and a rock shaft mounted in bearings on said bar and provided opposite each form with a projection adapted to cooperate with the overlapping sections of 35 the arms of the adjacent pair of bell crank levers to positively rock said levers into inoperative relation to the forms as said shaft is actuated.

6. In a garment drying and shaping means, 40 the combination of a plurality of drying forms, a bar supported by the forms and extending past all of them, means for clamping a garment on each form comprising a pair of bell crank levers fulcrumed on said bar, one arm of each said bell crank being adapted to cooperate with the form and the other arm of one lever having an outwardly projecting member, a spring connecting the members of each pair of bell cranks and adapted 45 to hold them in either operative or inoperative relation with the associated form, and a rock shaft journaled in bearings on said bar and provided with a plurality of fingers, one in alignment with each of the said outwardly 50 extending members on the bell cranks, whereby all of the clamps may be simultaneously moved into inoperative relation to the forms as said shaft is actuated.

7. In a garment drying and shaping means, 60 the combination of a plurality of substantially upright drying forms, a substantially horizontal bar extending throughout the series of forms near the lower ends thereof and supported by brackets projecting forward 65 from the forms, a pair of opposed bell cranks

pivotaly mounted on said bar adjacent each form, one member of each of said bell cranks being adapted to cooperate with the form to hold a garment in position thereon, a spring connecting each pair of bell cranks and acting 70 to hold said bell cranks in either operative or inoperative relation with the associated form, and a rock shaft journaled in bearings on said bar and provided opposite each form with a projection adapted to cooperate with one of the pair of bell cranks associated with that form to rock said bell cranks into inoperative position as the shaft is actuated.

In testimony whereof we have hereunto set 80 our hands.

EDWARD H. STEERE.
CLARENCE C. STEED.
